UNITED STATES PATENT OFFICE

110,011

DESIGN FOR A FRONT PANEL FOR AN ELECTRIC ARC WELDER

Clifford M. Akins, Minneapolis, Minn., assignor to Marquette Manufacturing Co., Inc., Minneapolis, Minn., a corporation of Minnesota

Application October 4, 1937, Serial No. 71,957

Term of patent 7 years

To all whom it may concern:

Be it known that I, Clifford M. Akins, a citizen of the United States, and a resident of Minneapolis, in the county of Hennepin and State of Minnesota, have invented a new, original, and ornamental Design for a Front Panel for an Electric Arc Welder, of which the following is a specification, reference being had to the accompanying drawing, forming part thereof:

Figure 1 is a perspective view of a front panel

for an electric arc welder showing my new design.

Figure 2 is a sectional view on the line 2—2 of Figure 1; and

Figure 3 is a perspective view of a portion of Figure 1 on an enlarged scale.

I claim:

The ornamental design for a front panel for an electric arc welder substantially as shown.

CLIFFORD M. AKINS.
